To all whom it may concern:

Be it known that I, ANNA K. The leading feature of my design comprises stripes and dots.

In the drawing, *a* is the body, *b* the border, and *a b* the complete carpet.

c are the stripes.

d are the dots.

The dots are arranged in generally rectangular forms with little figures dropped into each and the ground is well covered with the stripes.

The design of my invention will be best understood by reference to the accompanying drawing, and it may be expressed in different colors or combinations of colors and applied to velvet, Wilton, Brussels, ingrain, and other 25 carpets.

What I claim as my invention, and desire to secure by Letters Patent, is—

1. In a design for a carpet, the body *a*, substantially as shown. 30
  2. In a design for a carpet, the border *b*, substantially as shown.
  3. The design for a carpet consisting of the body *a*, and border *b*, substantially as shown.
- In testimony whereof I have hereunto signed my name.

ANNA K. MAY.
